Herbert Jager
Attn:

UNITED STATES PATENT OFFICE.

FRANK JAGER, OF CHICAGO, ILLINOIS.

GRAIN DOOR.

Application filed January 8, 1920. Serial No. 350,213.

To all whom it may concern:

Be it known that I, FRANK JAGER, a citizen of the United States, and residing at Chicago, county of Cook, and State of Illinois, have invented certain new and useful Improvements in a Grain Door, of which the following is a full, clear, and exact description, reference being had to the accompanying drawings, which form a part of this 10 specification.

My present invention relates to grain doors for railway freight cars, and has reference more particularly to the permanent type of grain door; one object being to improve the 15 construction and increase the efficiency and utility of doors of this type.

Another object of the invention relates to the provision of a sectional grain door whose parts are readily and singly shiftable 20 between the open and closed positions of the door, and when so shifted, the door occupies a minimum of space in the car. A further object resides in the fact that the door parts or sections while possessing the characteristic 25 of maximum strength and rigidity to withstand load pressures, they are nevertheless capable of being easily and cheaply fabricated and readily installed in the car.

A still further object of the invention is 30 the provision of a sectional door, as thus characterized, wherein the parts when in open position are so arranged that involuntary movement, due to abrupt train movement, is prohibited, and the possibility of 35 damage occurring to them from freight impact is reduced to the absolute minimum.

The invention also contemplates the provision of certain novel details of construction, combination and arrangement of the 40 improved door whereby the parts thereof are maintained or locked in closed position and a maximum of tightness at the joints obtained and maintained.

These, together with such other objects 45 and advantages as are hereinafter set forth, or are incident to my invention, I attain by means of a construction illustrated in a preferred form in the accompanying drawings; wherein:

50 Figure 1 represents an interior or rear elevation of the car siding and doorway to which my improved grain door is shown applied and in closed position;

Figures 2 and 3 are respectively views in longitudinal and vertical cross-section of the 55 door and doorway frame of Figure 1;

Figure 4 represents a front elevation of the door when closed;

Figure 5 is a view in perspective of fragmentary portions of the front door post and 60 door sections illustrating the gravity operated supplementary locking devices for the lower and intermediate door sections;

Figure 6 is a view similar to Figure 1 depicting the door in its full open position; and, 65

Figure 7 is a substantially similar view when the door is shown in a partially open or closed position.

In the drawings, the reference character 8 denotes the car siding, 8' the side plate, and 70 9 the fascie of a car of any suitable construction from which may be hung an outside door 10. Members defining the doorway frame, apart from that portion of the plate 8' overhanging the doorway opening, may desirably include the rear door post 11, the front door post 12 and threshold 13.

In the present instance, the grain door comprises the lower section A and the intermediate and upper grain door sections, B 80 and C respectively; the three sections being designed to fully close the doorway opening during grain shipment though under certain conditions of use, as in the transportation of coal, perhaps only the use of sections A and B may be contemplated in such a case.

This lower section is desirably provided with a grain discharge door 14 slidable to an open position whereby to initially provide 90 an outlet for the grain so as to relieve the door sections of load thrust and thereby permit of the use of grain scoops subsequent upon the shifting of the sections to clear the doorway opening. It is recessed to provide 95 a slideway 15 for the bar 16 whose lower end co-acts with an abutment 17 on the door 14 to hold the latter closed. The door section A is pivoted to the doorway frame as shown whereby it may be swung on its pivot 18 100 from its closed position in Figure 7, to the open position it occupies in Figure 6 of the drawings. This movement is steadied by means of a vertically disposed rod 19 extending from the floor to terminate at the 105 side plate 8', and which is, of course, spaced

away from the door post 11 to provide a clearance for the passage not only of the door section A but also the intermediate grain door section B in their opening and closing movements.

When in open position, the section B is carried in a slideway, mounted on the siding, and which in the present instance embodies the upper and lower slideway members 20, 20 arranged so as to permit the section to have longitudinal sliding movement from its open position shown in Figure 7 to its closed position in the doorway opening (Figure 1). In this position it is superimposed upon the lower section A, and it will be observed from an inspection of Figure 3 that the meeting edges of these sections are jointed or lapped, first, to provide a guideway 21 for the section B during its movement, and, second, to prevent leakage past this joint. It will also be noted in this connection that the inner side face of the forward door post 12 is also cut away to provide a full seat 22 for the reception of the front edge portions of both of these sections. If desired, a metal plate 23 may be secured against the inner face of the post to protect the shoulder 24 against wear from the grain scoop ropes. With the object in view of obviating leakage of grain past the rear edge portions of the sections A and B, the latter may desirably be provided with the wedges 25 and 26, respectively, whereby in the final closing movement of the sections these wedges co-act with the rod 19 to force said rear edge portions inwardly into a tight engagement with the doorpost 11, as will be understood.

The slideway members 20 terminate short of the doorway opening, thereby leaving sufficient space for the door section A to occupy when raised into its elevated open position against the front edge portion of the intermediate door section B, whose rear edge portion in turn abuts the stop 27. A latch 28 pivotally mounted on the upper slideway member 20 is positioned to engage an abutment 29 on the door section A so as to maintain it in its open position, and when so maintained obviously it holds the intermediate door section B against involuntary movement in a direction toward the doorway opening. This door section B is provided with rearward extensions 30, 30 which at all times slidably engage in the slideway, hence the guiding influence of the latter is always maintained and any possibility of the pilferage or unwarranted withdrawal of this section is thereby eliminated.

As will be seen from an inspection of the drawings, the upper section C is hingedly mounted on the side plate 8', or any other suitable overhead doorway frame member, to swing from its raised open position, indi-

cated in dotted lines in Figure 3, to its closed position disclosed in full lines in said figure, the hinges being denoted by the reference character 31, 31. The section is maintained in its elevated position by means of any suitable latching device, such as that indicated at 32, and its lower meeting edge portion is preferably lapped with the upper edge of the section B (Figure 3) to define a seat 33 limiting outward movement of section C and eliminating the possibility of leakage past this joint. A gravity locking element 34 is slidably set into the outer face of section C whose bent lower end 34' constitutes a hand-hold whereby said end may be elevated clear of the recess 35 in which it is normally seated for the purpose of holding both door sections B and C in closed position. When this element 34 is thus raised, both doors may be moved to their open positions, and when so moved the section A may then in turn be swung to open position on its pivot. It should be observed that the vertical rod is positioned so as not to interfere with the movement of door section C. If desired, gravity locking members 36 and 37 may additionally be employed for the grain door sections A and B, respectively, the former for locking the section A when used separately for coal and both when these sections are employed in group form without the hinged section C. Furthermore, the lower section when in raised position is preferably arranged so as to leave a space between its bottom edge and the floor to clear any pieces of coal that may have been left in the car.

Assuming the door is in open position, it will be obvious from the foregoing description that upon the release of the latch 28 the section A may be swung downwardly on its pivot 18 into its closed position as shown in Figure 7, whereupon sliding movement is imparted to the section B longitudinally of the slideway and the guideway in the upper edge of the section A to bring it, in turn, into its operative closing relation with the doorway opening. Incident to the completion of these movements, the locking members 36 and 37 automatically engage the sections to positively maintain their operative relation which latter is rendered more effective by the lapped joints and the wedging action afforded by the co-operation between wedges 25, 26 and the rod 19. Upon release of the latch 32, the upper section C drops into place, and in its final closing movement the bent end 34' of the locking element 34 is cammed up and falls into its seat. When thus seated, element 34 locks both sections B and C independently of the members 36 and 37, and obviously the lower section is immovable with the others superimposed upon it. Inasmuch as

the steps taken in the opening of the door sections are exactly the reverse of those taken in their closing, no further explanation is deemed necessary.

5. It will be apparent that destructive nail-
ing of parts to the doorposts, as is neces-
sarily done with temporary grain doors, is
wholly obviated. This customary practice,
apart from occasioning damage to the posts,
10 is wasteful in the extreme, and obviously so
in view of the constant scraping of these
temporary doors after a single trip. My
door, comprising as it does a series of mo-
bile sections, each having its appointed
15 place of storage when not in use, is easily
handled and in the shortest possible time
at grain chutes and elevators. It is simple
in construction, possesses maximum strength
and rigidly prevents leakage of grain past
20 contacting surfaces, is fool-proof and easily
installed, and the parts are readily fabri-
cated and as readily replaced should that
become necessary. Other advantages, it is
believed, will be apparent to others skilled
25 in this art.

I claim:

1. In a railway freight car, the combina-
tion of a doorway frame providing a door
opening, of a sectional grain door for said
30 opening comprising a door section pivoted
at one side of said opening and adapted to
swing from horizontal position across said
opening to a vertical position at one side of
35 said opening, a longitudinally slidable door
section mounted in the same vertical plane
as the pivoted section and at the same side
of the door opening and adapted when in
closed position to be disposed upon the up-
40 per edge of said pivoted section, and means
for guiding and supporting said slidable
section, said means being remote from the
doorway opening so as to permit said piv-
oted section when in opened position to be
45 disposed between said means and said door-
way opening.

2. In a railway freight car, the combina-
tion with the doorway frame and its open-
ing, of a sectional grain door for said open-
ing comprising a pivoted door section move-
50 able into said opening, a longitudinally slid-
able door section movable along the upper
marginal edge of said pivoted door section
into its closed position in the doorway open-
ing, and a third door section hinged-
55 mounted on the upper portion of the door-
way frame whereby to swing downwardly
and engage the upper marginal edge of the
slidable door section.

3. In a railway freight car, the combina-
tion with the doorway frame and its open-
ing, of a sectional grain door for said open-
ing comprising a pivoted door section dis-
posed in closed position in said opening, a
longitudinally slidable door section movable

along the upper marginal edge of said piv-
oted door section into its closed position in
the doorway opening, a third door section
hingedly mounted on the upper portion of
the doorway frame whereby to swing down-
wardly and engage the upper marginal 70
edge of the slidable door section, the latter
serving to maintain the pivoted door sec-
tion in its closed position, and means for
holding the other door sections against
opening movement. 75

4. In a railway freight car, the combina-
tion with the doorway frame and its open-
ing, of a sectional grain door for said open-
ing comprising a door section pivoted to
swing into said opening, a longitudinally 80
slidable door section movable along the up-
per marginal edge of said pivoted door sec-
tion into its closed position in the doorway
opening, a third door section hingedly
mounted on the upper portion of the door-
85 way frame whereby to swing downwardly
and engage the upper marginal edge of the
slidable door section, the latter serving to
maintain the pivoted door section in its
closed position, and means for holding the
90 other door sections against opening move-
ment, the forward marginal edge portions
of the pivoted and slidable door sections
being seated, when in closed position, in one
of the doorway frame members. 95

5. In a railway freight car, the combina-
tion with the doorway frame and its open-
ing, of a sectional grain door for said open-
ing including a pivotally mounted door sec-
tion adapted to be swung across said open-
ing, a longitudinally slidable door section
100 movable along the upper marginal edge of
said pivoted door section into its closed posi-
tion in the doorway opening, a third door
section hingedly mounted on the upper por-
tion of the doorway frame whereby to swing
105 downwardly and engage the upper marginal
edge of the slidable door section, the latter
serving to maintain the pivoted door section
in its closed position, means for holding the
110 other door sections against opening move-
ment, the forward marginal edge portions
of the pivoted and slidable door sections
being seated, when in closed position, in one
of the doorway frame members, and means
115 for causing the rear marginal edge portions
of said pivoted and slidable door sections to
simultaneously tightly engage the opposite
doorway frame member.

6. A grain door for the doorway opening 120
of a freight car comprising a lower door sec-
tion pivoted at one side of said opening to
be swung from its horizontal closed posi-
tion across the threshold of the doorway to
a vertical position adjacent the opening, and
125 a second door section adapted to be superim-
posed upon said lower section when in closed
position and mounted in the same vertical

plane as the lower section to slide transversely of the opening from its closed position to its open position clear of said opening a sufficient distance to permit the lower 5 door section when in open vertical position to be interposed between the second door section and the doorway opening.

7. A grain door for the doorway opening of a freight car comprising a lower door section arranged to be swung from its horizontal closed position across the threshold of the doorway to a vertical position adjacent the opening, and a second door section adapted to be superimposed upon said lower 10 section when in closed position and to have sliding movement transversely of the opening from its closed position to its open position clear of said opening, the lower door section when in open vertical position being 15 interposed between the second door section and the doorway opening, and a third door section adapted to be superimposed upon the second door section when the latter is in closed position and hingedly mounted for 20 upward swinging movement to clear said second door section whereby to permit the latter to have sliding movement to its open 25 position.

8. A grain door for the doorway opening of a freight car comprising a lower door section arranged to be swung from its horizontal closed position across the threshold of the doorway to a vertical position adjacent the opening, and a second door section 30 adapted to be superimposed upon said lower section when in closed position and to have sliding movement transversely of the opening from its closed position to its open position clear of said opening, the lower door section when in open vertical position being 35 interposed between the second door section and the doorway opening, said second door section serving to maintain the lower door section in its closed position and the latter 40 operating to prevent involuntary movement of the second door section from its open position into the doorway opening.

9. In a freight car, the combination with the doorway frame and its opening, of a 45 slideway extending longitudinally of the car siding toward said opening, a pivoted lower grain door section adapted to be horizontally disposed in said opening when in closed position, there being a space between the slideway and the doorway opening into 50 which said section may be moved whereby it assumes a vertical open position clear of said opening, and a second door section movable from its open position in said slideway to its closed position in said opening above 55 said pivoted door section.

10. In a freight car, the combination with the doorway frame and its opening, of a 60 slideway extending longitudinally of the

car siding toward said opening, a pivoted 65 lower grain door section adapted to be horizontally disposed in said opening when in closed position, there being a space between the slideway and the doorway opening into which said section may be moved whereby it assumes a vertical open position clear of 70 said opening, and a second door section movable from its open position in said slideway to its closed position in said opening above 75 said pivoted door section, said second door section provided with a rearward extension engaging said slideway when said section is in its closed position in the opening.

11. In a freight car, the combination with the doorway frame and its opening, of a 80 slideway extending longitudinally of the car siding toward said opening, a pivoted lower grain door section adapted to be horizontally disposed in said opening when in closed position, there being a space between the slide- 85 way and the doorway opening into which said section may be moved whereby it assumes a vertical open position clear of said opening, a second door section movable from its open position in said slideway to its closed position in said opening above 90 said pivoted door section, said second door section provided with a rearward extension engaging said slideway when said section is in its closed position in the opening, means en- 95 gaging the free end of said pivoted door section for holding the section in its open position, said pivoted section and said means co-operating to maintain the second door section against movement toward the doorway opening, and a third and upper grain door section hingedly mounted on the doorway frame above the opening for downward movement to engage the upper edge portion 100 of the second grain door section when the latter is closed, the meeting edges of said sections, having their joints broken to prevent leakage of grain.

12. In a railway freight car, the combination with the doorway frame members defining the doorway opening, of a two-part slide- 110 way extending longitudinally of the car wall toward said opening but terminating short of said opening to provide a space therebetween, a lower grain door section pivotally mounted on the rear doorway frame member to swing from its open position in said space to its closed position and having a guideway in its upper edge portion, a vertically disposed rod spacedly confronting the rear 115 doorway frame member whereby to guide said section during its opening and closing movement, an intermediate grain door section movable from its open position in said slide- 120 way to its closed position in the opening and adapted during its closing movement to have its lower edge portion to slide in said guideway, both said sections when closed hav- 125

ing their forward edge portions seated in the front doorway frame member and their rear edge portions forced tightly against said rear doorway frame member by said rod, a third and upper grain door section hinged for swinging movement clear of the rod to its closed position where its lower edge portion laps over the upper edge portion of the intermediate section, the latter provided with extensions engaging the slideway in the closed position of the section, and means for maintaining the sections in their open and closed positions.

FRANK JAGER.
